INVENTOR
Noble M. Johnson
General Electric

ATTORNEY.

UNITED STATES PATENT OFFICE

NOBLE M. JOHNSON, OF DETROIT, MICHIGAN

INTERNAL-COMBUSTION ENGINE

Application filed March 16, 1927. Serial No. 175,716.

This invention relates to improvements in internal combustion engines.

It is an object of this invention to provide an internal combustion engine wherein cam plates, mounted one on each side of a main casing in which cylinders are arranged, are rotated by pistons in the cylinders thereby doing away with the usual crank shaft; and also to provide openings through the cam plates so that the latter are also utilized as intake and exhaust valves thereby eliminating all the usual valve gear.

With these and other objects in view which will be mentioned as the specification proceeds, a preferred embodiment of the invention is hereinafter more fully described with the aid of the accompanying drawings, in which:

Figure 1 illustrates a side elevation of the invention partly in section.

Figure 2 is a section on the line 2—2 of Figure 1.

Figure 3 is a side view of one of the cam plates.

Figure 4 shows a side view of one of the manifolds, and

Figure 5 is a partial end view of the invention.

Referring to the drawings, 1 designates a stationary main case having a central bearing 2 therethrough for a drive shaft 3, and an annular outer portion 4. Between the bearing 2 and the outer portion 4, and sometimes integral with both, are a plurality of cylinders 5. These cylinders extend inwards from the outer portion 4 and are connected to the bearings 2 by arms 6. In the inner ends of the cylinders are walls 7, which may be integral with the main casing, and on the periphery of the latter cylinder covers 8 are attached. 9 indicates spark plugs which extend into the cylinders. In each cylinder is a usual piston head 10 having a rod 11 extending inwardly therefrom through an opening in its wall 7. The inner ends of the rod 11 have openings therethrough to receive pins 12 which latter project beyond the sides of the casing between the arms 6.

Mounted on the drive shaft 3, one on each side of the main casing and usually of slightly

smaller diameter than the latter, are two cam plates 13 and 13^a. In the inner side of these cam plates are cam slots 14 and 14^a usually substantially elliptical which receive the ends of the pin 12. 15 denotes slides which are preferably provided around the ends of the pin 12. The cam plates are keyed or otherwise secured to the drive shaft 3 as by keys 16 and 16^a. Through the sides of the cam plates are openings 17 and 17^a which register in turn with each of the inlet and exhaust ports 18 and 18^a respectively in the sides of the cylinders towards their outer ends.

The outer surfaces of the cam plates are supported by intake and exhaust manifolds 19 and 19^a respectively which are annular and have inwardly projecting flanges 20 and 20^a secured to the periphery of the casing. The manifolds also have inlet and exhaust openings 21 and 21^a respectively usually on their outer surface, and through them ports 22 and 22^a are provided which are positioned opposite the ports 18 and 18^a through the sides of the cylinders, so that as the cam plates turn combustible mixture passes from the intake manifold 19 through the ports 22, opening 17 and ports 18 into each cylinder in turn, and from the latter through the ports 18^a, opening 17^a and ports 22^a into the exhaust manifold 19^a.

It is believed that the operation of the engine will be readily understood from the foregoing description, which briefly is as follows:

Combustible mixture is supplied to the intake manifold 19 through the inlet 21. This manifold has ports 22 through its inner surface, one opposite each of the cylinder inlet ports 18 but normally separated from the latter by the cam plate 13. The cam plate has, in the embodiment shown, one passage 17 therethrough so positioned that as the plate rotates each manifold port 22 in turn is in communication with its cylinder port 18. The action of each piston and cylinder unit is identical to that of any other four stroke engine. The explosive stroke of each piston forces its rod 11 and pin 12 downwards thereby causing the cam plates 13 and 13^a to rotate. It will be noted that the centre lines of the cylinders are not radial with the centre line of the cam

plates, though one side of each cylinder wall may be radial thereto. The cam plates are so set on the drive shaft 3 that their openings 17 and 17^a are in such relative positions that the opening 17^a connects each cylinder exhaust port 18^a with its exhaust manifold port 22^a on the upstroke of the pistons following their working strokes.

In the foregoing the simplest form of construction is shown and described, though obviously the cams may be so shaped that two or more explosive strokes will occur during each revolution of the cam plates. In that case the number of openings 17 and 17^a must equal the number of working strokes per revolution of the cam plates.

While in the foregoing the preferred construction has been described and shown, it is understood that modifications may be made therein provided they fall within the scope of the appended claims.

What I claim is:

1. In an internal combustion engine, the combination of a main casing, a shaft revolvably supported therein, cylinders in said casing having inlet and exhaust ports therein, pistons in said cylinders, piston rods connected to said pistons, plates fixed on said shaft having cam slots therein, pins through said piston rods taking into said cam slots which latter are so shaped that said plates are forced through part of a revolution on each working stroke of each piston, one side of each plate bearing against one set of cylinder ports, intake and exhaust connections against which the sides of said plates remote from said cylinders bear, and said plates having passages therethrough by which each cylinder inlet or exhaust port is connected to each of the inlet and exhaust connections in turn as said plates turn.

2. In an internal combustion engine, the combination of a main casing, a shaft rotatably mounted therein, cylinders substantially radially arranged in said casing, pistons in said cylinders, piston rods connected to said pistons, plates fixed on said shaft having substantially elliptical cam slots therein, pins through the inner ends of said piston rods extending into said cam slots so that the movement of said pistons is adapted to rotate said plates, an annular intake manifold and an annular exhaust manifold supported by said casing, said cylinders having inlet and exhaust ports therein, said manifolds having openings, and said plates having passages therethrough adapted to connect each cylinder inlet port and each cylinder exhaust port in turn with an intake or exhaust manifold opening.

3. In an internal combustion engine, the combination of a rotatable shaft, a housing for the shaft having inlet and exhaust manifolds and cylinders and pistons therein, cam members fixed to said shaft, said cam mem-

bers having valve slots therein adapted to register with inlet and exhaust ports in said manifolds and said cylinders, and said cam members each having a cam groove on adjacent faces of the cam members and adapted to cooperate with pins carried by said pistons for driving said shaft.

NOBLE M. JOHNSON.
